UNITED STATES PATENT OFFICE.

JOHN L. DAWES, OF PITTSBURGH, PENNSYLVANIA.

DESIGN FOR A LAMP-CASING.

50,239.

Specification for Design.

Patented Jan. 30, 1917.

Application filed November 17, 1916. Serial No. 131,966. Term of patent 7 years.

To all whom it may concern:

Be it known that I, JOHN L. DAWES, a citizen of the United States, residing at Pittsburgh, in the county of Allegheny and State of Pennsylvania, have invented a new, original, and ornamental Design for Lamp-Casings, of which the following is a specification, reference being had to the accompanying drawings, forming part thereof, in which—

ing embodying my new design; and Fig. 2 is a plan view of my new design.

I claim:

The ornamental design for a lamp casing, as shown.

In testimony whereof, I have hereunto set my hand.

JOHN L. DAWES.
